UNITED STATES PATENT OFFICE.

ERNEST WALBRECKER, OF WYOMISSING, PENNSYLVANIA, ASSIGNOR TO THE NARROW FABRIC COMPANY, OF WEST READING, PENNSYLVANIA, A CORPORATION OF PENNSYLVANIA.

DESIGN FOR FABRIC RIBBON.

Application filed September 19, 1923. Serial No. 7,272. Term of patent 7 years.

To all whom it may concern:

Be it known that I, ERNEST WALBRECKER, a citizen of the United States, residing at Wyomissing, in the county of Berks and State of Pennsylvania, have invented certain original and ornamental Design for Fabric Ribbon, of which the following is a specification, reference being had to the accompanying drawing, forming part thereof.

The figure is a plan view of a piece of fabric ribbon constituting my design.

I claim:

The ornamental design for fabric ribbon, as shown.

In testimony whereof I affix my signature.

ERNEST WALBRECKER.
